SAFETY DEVICE FOR BOILERS

Fred Lee Badgett, Chickasha, Okla., assignor to
Badgett Steam Lubricator Company, Chicka-
sha, Okla., a corporation of Oklahoma

Application June 8, 1931. Serial No. 542,846

4 Claims. (Cl. 137—144)

My invention relates to automatic heat-control apparatus and more particularly to a safety device for boilers, the principal object of the invention being to provide apparatus of this character for automatically cutting off the supply of fuel and draft to a boiler when the water level in the boiler reaches a dangerously low mark.

In accomplishing this and other objects of my invention I have provided improved details of structure, the improved form of which is illustrated in the accompanying drawings, wherein:

Fig. 1 is a perspective view of a boiler equipped with fuel and draft control mechanism embodying my invention.

Fig. 2 is a plan view of a thermostat assembly, parts thereof being shown in central section to more clearly disclose the structure of the device.

Fig. 3 is a rear elevational view of the thermostat assembly.

Fig. 4 is a cross section on the line 4—4, Fig. 2.

Fig. 5 is an elevational view of a fuel and draft control, the greater portion of the device being shown in central vertical section to illustrate the operation of the valves.

Fig. 6 is a plan view of the fuel and draft control unit.

Fig. 7 is a cross section of the line 7—7, Fig. 5. Referring more in detail to the drawings:

1 designates a boiler including a fire box 2, a steam dome 3 and a smoke stack 4.

The mechanism for controlling the supply of fuel to the fire box of the boiler, and the supply of draft to the stack, comprises a thermostat assembly 5 and a control unit 6, each of which will now be described in detail.

The thermostat assembly is mounted adjacent one side of the boiler slightly below the water level thereof with the front end of the thermostat at a lower elevation than the rear end, as shown in Fig. 1 of the drawings, and comprises a supporting plate 7 having an opening 8 near its approximate center for slidably receiving a thermostat tube 9 mounted in spaced relation within a casing 10 and retained in concentric sliding relation therewith by inwardly extending guide bosses 11 fixed in the casing by means such as welding, as indicated at 12.

Fixed to the rear end of the casing, preferably by welding, are supporting bolts 13 adapted to extend through a series of openings 14 surrounding the opening 8 in the supporting plate. Adjusting nuts 15 threaded on the bolts and

engaging opposite faces of the plate are provided for varying the inclination of the casing and thermostat with relation to the supporting plate and boiler. The opposite end of the casing is externally threaded, as shown at 16, for engaging the internal threads 17 of a reducer coupling 18 having an intermediate web 19 provided with an internally threaded opening 20 for receiving the forward end of the thermostat tube.

In this manner the front end of the thermostat remains fixed while its opposite end is free to slide through the opening 8 of the supporting plate when expanded or contracted due to variations of temperature. Ventilating ports 21 are provided in the casing to permit circulation of air around the outer surface of the thermostat.

The end of the supporting plate nearest the opening 8 is provided with an opening 22 for receiving the nipple 23 of a valve housing 24 secured to the plate by a nut 25 threaded on the nipple and engaging the plate.

An annular seat 26 is provided in the valve housing for cooperating with the conical end 27 of a valve stem 28 extending through a concentric opening 29 in the nipple and retained in sealed sliding relation with the nipple by packing material 30 seated in a counterbored opening 31 of the nipple and urged into engagement with the stem by a gland 32.

The opposite end of the supporting plate is provided with a series of spaced openings 33 for selectively receiving a fulcrum rod 34 yieldingly and adjustably retained in the plate by a spring 35 mounted on the rod between inner and outer bearing washers 36, and by adjusting nuts 37 and 38 threaded on the rod and respectively engaging the front face of the supporting plate and the outer bearing washer.

A bearing head 39, having a relatively wide slot 40 for receiving a lever arm 41, is threaded on the rear end of the fulcrum rod and is fixed thereto by a jam nut 42.

A longitudinal series of openings 43 is provided in the lever arm for selectively aligning with the transverse openings in the bearing head, a headed pin 45 being extended through the arm and bearing head and secured thereto by a cotter pin 46.

Threaded on the free end of the thermostat tube is a similar bearing head 47 including an inner enlarged end 48 provided on its upper face with an inlet opening 49 for receiving a steam line communicating with the tube. The

valve stem is also provided with a bearing head 51 identical in structure to the head 39 and fixed to the stem by a nut 52, slots 53 being provided in each of the heads 47 and 51 for the lever arm 41 which is pivotally mounted therein by cross pins 54.

Engaging the reduced internally threaded end of the coupling 18 is a conduit 55 leading into the side of the boiler, as shown at 56, and provided with a valve 57 and with a drain 58, a drop 59 being formed in the line to serve as a trap for preventing hot water in the line 55 adjacent the boiler from working through the cooler water in said line adjacent the thermostat.

The fuel and draft control unit 6 is operated by the thermostat assembly and includes a valve 60 interposed in a fuel supply line 61 leading to a burner (not shown) inside the fire box, and a valve 62 is interposed in a line 63 leading from the steam dome of the boiler to a blower 64 extending into the stack 4.

Each of the valves is provided with the usual neck 65, the neck of the valve 60 extending through an opening 66 formed in a supporting plate 67 adjacent one end thereof and the neck of the valve 62 extending through an aligning opening 68. Clamping nuts 69 are threaded on each of the stems into engagement with the supporting bar for securing the valves to the bar.

Provided in the housing 60 is an inwardly directed flange 70 having a conical seat 71 for cooperating with a valve 72 including a guide 73 slidably extending through the seat opening. A valve stem 74 secured to the valve extends through a concentric opening 75 of the neck and is maintained in sealed sliding relation therewith by packing 76 urged into a counterbored opening 77 of the neck by a gland 78.

Spaced bracket arms 79 formed integrally with the clamping nut 69 of the valve 60 are joined at their upper ends by a cup 80 having a concentric opening 81 for receiving a guide 82 formed integrally with the upper end of a bearing head 83, said head being threaded on the upper end of the valve stem 74 and maintained in adjusted relation therewith by a lock nut 84 threaded on the stem.

A slot 85 in the head 83 includes a lower wall 86 having a knife edge 87 serving as a bearing surface for a lever arm 88 extended into the slot and limited in its upward movement by a cross pin 89 inserted through transverse aligning openings 90 of the head.

The structure of the valve 62, with the exception of being smaller in size, is preferably identical to the valve 60 and includes a stem 91, projecting through a packing gland 92 provided on the outer end of the neck 65, and having an upper threaded end 93 for receiving a bearing head 94 locked on the stem by a jam nut 95.

Provided adjacent the opposite end of the supporting plate is an opening 96 for adjustably receiving a fulcrum rod 97 threaded throughout its greater portion so that a spring 98 may be mounted on the stem on the lower side of the supporting bar between bearing washers 99 and retained thereon in adjusted position by a nut 100, a similar adjusting nut 101 being threaded on the stem against the opposite or upper face of the bar.

A bearing head 102 similar to the head 94 is threaded on the extreme upper end of the rod 97 and locked thereon by a jam nut 103, and each

of the heads 94 and 102 are provided with relatively wide slots 104 for receiving the lever arm 88, transverse pins 105 and 106 being extended through the respective heads and through the bar for pivotally connecting the bar to the heads. 80

From the foregoing it will be apparent that the operation of the valves is dependent upon each other and that means for closing the larger valve would serve to close the smaller valve. This actuating means is preferably provided on the larger valve and includes a cylinder 107 threaded into the upwardly directed opening 108 of the cup member 80 and adapted to receive a piston 109 comprising a pair of opposing cup members 110 clamped by a nut 111 against the head 112 of a bolt 113. 85

In order to yieldingly urge the piston to its uppermost position under normal conditions a spring 114 is mounted in the cup member with its upper end bearing against a retaining washer 115 anchored to the guide portion 82 of the head 83 by a bolt 116 adjustably secured to the guide by a nut 117. 90

Threaded into an opening 118 formed in the upper end of the cylinder is a steam line 119 leading into the lower opening of the valve housing 24 of the thermostat assembly. From the upper end of this valve a conduit 120 leads into the top end of the boiler and is provided with a valve 121 and with a T-fitting 122 from which a branch 123 leads to the inlet opening 49 of the thermostat. A T-fitting 124 is also provided in the line 119 for receiving a branch pipe 125 provided with a relief valve 126. 100

The operation of a boiler equipped with a thermostat assembly and with a fuel control unit constructed and assembled as described would be as follows:

As long as the water level in the boiler is maintained at a proper height the entire thermostat tube, or a sufficient portion thereof, will be filled with water to cause contraction of the tube which, in turn, closes the valve 24. This position of the valve 24 prevents pressure of steam in the line 120 from being exerted on the piston in the cylinder 107 and, consequently, the valves 60 and 62 remain in open position to permit uninterrupted supply of fuel to the burner in the fire box of the boiler and a continuous supply of steam to the blower in the stack. 115

Should the water level in the boiler reach a dangerously low mark, the water in the thermostat tube will recede and a greater portion of the tube will be filled with steam from the line 120 which will cause expansion of the tube and consequent opening of the valve 24. 120

With the valve 24 in this position steam from the line 120 is free to flow through the line 119 to depress the piston 109 in its cylinder against tension of the spring 114. This downward movement of the piston will close each of the valves 60 and 62, thereby preventing admission of fuel to the fire box of the boiler and supply of steam to the blower in the stack. 130

Consequently, the boiler will at all times be protected against a dangerously low water level which would expose the crown sheet or flues of the boiler to excessive heat and result in explosion of the boiler and possible injury to life. 140

What I claim and desire to secure by Letters Patent is:

1. Apparatus of the character described including a plurality of valve housings having neck portions, a supporting bar having openings for receiving said neck portions, means

for securing said neck portions to the bar, valves in the housings having stems, a lever anchored to the bar and operatively connected with the stems, and pressure-responsive means for actuating said lever to simultaneously operate the valves.

2. Apparatus of the character described including a valve housing having a neck portion a support having an opening for receiving said neck portion, a nut for clamping the neck portion to the support, a valve in the housing have a stem extended through the nut, and fluid-pressure responsive means including a cylinder carried by the nut and a piston slid-
able in the cylinder and operatively connected with the valve stem for actuating said valve.

3. Apparatus of the character described including a valve housing having a neck portion, a support having an opening for receiving said neck portion, a nut for clamping the neck portion to the support, a valve in the housing hav-
ing a stem extended through the nut, fluid-

pressure-responsive means including a cylinder carried by the nut and a piston slid-
able in the cylinder and operatively connected with the valve stem for actuating said valve, a second valve mounted on the support having a stem, a lever having one end anchored to the support and its opposite end connected with the first named stem, and means operatively connecting the stem of the second valve with the lever to effect operation of the second valve simultaneously with actuation of the first named valve.

4. Apparatus of the character described including a pair of valves having stems, a support for the valves, a bearing head on one stem having a transverse slot, a wall in said slot having a knife edge, a lever anchored to the support and extended through said head for bearing engagement with said knife edge, means for operatively connecting the lever with the other valve stem, and pressure-responsive means for actuating the lever to operate the valves.
